(57) **CLAIM**

The ornamental design for a plant pot holder, as shown and described.

DESCRIPTION

FIG. 1 is a perspective view of a plant pot holder according to the present invention.

FIG. 2 is another perspective view thereof.

FIG. 3 is another perspective view thereof.

FIG. 4 is another perspective view thereof.

FIG. 5 is a side elevation view thereof.

FIG. 6 is another side elevation view thereof.

FIG. 7 is a top plan view thereof; and,

FIG. 8 is a bottom plan view thereof.

1 Claim, 8 Drawing Sheets

FIG. 1

FIG. 2

FIG. 3

FIG. 4

FIG. 5

FIG. 6

FIG. 7

FIG. 8
